MATRIX FOR STRIP-MATERIAL FACES.

1,298,900.

Specification of Letters Patent.

Patented Apr. 1, 1919.

Application filed September 17, 1918. Serial No. 254,395.

To all whom it may concern:

Be it known that I, WALTER R. COZATT, a citizen of the United States, residing at Oakland, in the county of Alameda and State of California, have invented new and useful Improvements in Matrices for Strip-Material Faces, of which the following is a specification.

The present invention relates to improvements in matrices for casting faces in metal strip material such as are used on a type or slug casting machine.

At present it is the practice to provide a separate matrix for each style of face.

The object of the present invention is to provide a matrix having a single body or holder and a casting portion which can be varied so that a large number of different styles of printing faces can be cast thereby, thereby effecting a great saving.

In the accompanying drawing, Figure 1 is a plan view of the matrix; Fig. 2 is a perspective view thereof; Fig. 3 is a longitudinal sectional view on the line 3—3 of Fig. 25 1; Fig. 4 is a cross-sectional view on the line 4—4 of Fig. 1; Fig. 5 is a perspective view of a packing piece used therein; Fig. 6 is a similar view of a packing piece used on the side of the matrix opposite to the packing 30 piece shown in Fig. 5; Fig. 7 is a similar view of a space liner; Fig. 8 is a similar view of a face liner; Fig. 9 illustrates a number of different faces selected from the whole 35 number which can be cast from a single matrix of my invention.

On referring to the drawing, it will be seen that my improved matrix is compounded of several different pieces. The main piece is a holder 1, rectangular in plan view, and the length of which is identical with those at present in use in the monotype machine, while the width is preferably a trifle less, as .395 inch.

The middle portion of said holder is recessed to a considerable depth, the ends 2 of said recess being undercut. In this recess is inserted on one side a packing piece 3 of 45 constant width, namely, .1585 inch. This

packing piece, as well as all the pieces hereinafter described which are contained in said recess, is of the same length as the recess and is formed with beveled ends 4 to fit snugly against the undercut ends of the recess. The packing piece 3 is preferably inserted first in the recess. The casting face of the matrix 55 is then made up by means of space liners 5 and face liners 6. These space liners and face liners vary in thickness according to the face which it is desired to cast from the matrix, the space liners being, of course, of greater depth than the face liners. Suppose that it is required to cast the face indicated at 9^a in the series of faces 9 illustrated in Fig. 9, there is placed in the holder 1 by the side of the packing piece 3, first, a face 65 liner 6 of the thickness of about .005 inch, then a space liner 5 of .0138 inch thickness, then a face liner 6 of .0138 inch thickness, then a space liner 5 of .0138 inch thickness, and then a face liner 6 of about .005 inch 70 thickness.

One or more side packing pieces 7 are then inserted in the recess in the matrix. The thickness of this packing piece or pieces 7 depends upon the face required, and I provide, for thus closing the matrix, packing pieces of three different thicknesses, namely, .1585, .083 and .0553. Thus, a matrix having a two-point face would be closed by using packing pieces of .1585 and .0553 inch in 75 thickness. In all cases packing pieces 7 are selected which will, with the packing piece 3 and the liners 5, 6, have a combined thickness of .4 inch, so that packing pieces 3 and 80 7 project slightly beyond the sides of the holder 1, and thereby they are pressed inward by the packing pieces of adjacent matrices, so that the liners and packing pieces fit tightly against each other.

One end of the holder is at the same level 90 at the top as the packing pieces 3 and 7, while the other end is recessed to provide a surface 8, which, though in approximately the same plane as the casting face of the face liner, is sufficiently low as shown in the 95 drawing, or sufficiently high when the holder

is inverted for casting, or, in other words, sufficiently near to the opposite side of the holder, to permit the rule face cast by the face liner to pass by said surface 8 without 5 contacting therewith, so as to allow the cast face to pass out without being injured. As herein shown, said surface 8 extends nearly the whole width of the holder, but it is only necessary that it should extend throughout 10 a width slightly greater than the thickness of the face liner, its only object being to permit the ready passage of the face cast from said face liner. Thereby a rule face can be formed of any length by successively casting 15 the several sections thereof and moving them past said surface 8. Face and space liners may be provided of any thickness desired, but I propose to provide with one holder the following face liners, namely:— 20 three of a thickness of one-third of a point; three of one-half of a point; three of 1 point; two of 2 points; and one each of 3, 4, 5, 6, 8, 10 and 12 points; and the following space liners, namely: three of the thickness 25 of one-half of a point, three of 1 point, and three of 2 points. With this outfit, faces can be cast of almost an infinite number of designs.

It will be seen that the compound matrix 30 herein described, while capable of casting a great variety of faces, 9, some of which are illustrated in Fig. 9, can be made comparatively cheap, as the cost of the holder is not great, and all the remaining parts can be 35 made at comparatively small expense.

As shown in Figs. 2 and 3 of the drawing, there is a slight taper of about .002 of an inch, in the thickness of the mediate or thin portion of the holder 1, the rear end of this 40 thin portion being thinner than the front end thereof. The liners are of uniform depth throughout. The space in which the printing face is cast extends only through the rear half of the length of the recess in 45 the holder, each casting, after it is made, being moved to the front half of said recess to make room for the next casting. It results from the above-mentioned taper that the rear portion of each casting is about .001 of 50 an inch higher than its front portion. But, in being moved to the front portion of the recess, said rear portion of the printing face is pressed or smoothed down, so that the rear portion of an advancing casting and the 55 front portion of a succeeding casting, are, as it is termed "burnished" together as the rule is pushed through the matrix, thereby insuring a perfectly continuous line of any length in the printing face however many 60 castings may be used to form said line or printing face. The same result can be obtained by making the thin portion of the holder uniform in thickness and tapering the

liners toward the rear end. This construction would, however, be more expensive and 65 inconvenient than the one here shown.

I claim:

1. A compound matrix comprising a holder having in its face a longitudinally extending recess and a face liner and side 70 packing pieces extending longitudinally in said recess, said holder being provided with means for retaining said liner and packing pieces in said recess, and an end of the holder having the surface which is most 75 nearly in the same plane as the casting face of the face liner sufficiently near the opposite side of the holder to permit the rule face cast by said face liner to pass in a longitudinal direction by said portion of the 80 surface without contacting therewith.

2. A compound matrix comprising a holder having in its face a longitudinally extending recess with under-cut ends, and a face liner and side packing pieces contained 85 in said recess and having ends fitting snugly in the under-cut ends of the recess, and an end of the holder having the surface which is most nearly in the same plane as the casting face of the face liner sufficiently near to 90 the opposite side of the holder to permit the rule face cast by said face liner to pass in a longitudinal direction by said portion of said surface without contacting therewith.

3. A compound matrix comprising a 95 holder having in its face a longitudinally extending recess with under-cut ends, and a face liner, a space liner and side packing pieces contained in said recess and having ends fitting snugly in the under-cut ends of 100 the recess, and an end of the holder having the surface which is most nearly in the same plane as the casting face of the face liner sufficiently near to the opposite side of the 105 holder to permit the rule face cast by said face liner to pass in a longitudinal direction by said portion of said surface without contacting therewith.

4. A compound matrix comprising a 110 holder having in its face a longitudinally extending recess having under-cut ends, and a face liner, space liners and side packing pieces contained in said recess and having 115 ends fitting snugly in the under-cut ends of the recess, and an end of the holder having the surface which is most nearly in the same plane as the casting face of the face liner sufficiently near to the opposite side of the 120 holder to permit the rule face cast by said face liner to pass in a longitudinal direction by said portion of said surface without contacting therewith.

5. A compound matrix comprising a holder having in its face a longitudinally extending recess having under-cut ends, and 125 face liners, space liners and side packing

pieces contained in said recess, and having ends fitting snugly in the under-cut ends of the recess, and an end of the holder having the surface which is most nearly in the same plane as the casting face of the face liner sufficiently near to the opposite side of the holder to permit the rule face cast by said face liner to pass in a longitudinal direction by said portion of said surface without con-
10 tacting therewith.

6. A compound matrix comprising a holder having in its face a longitudinally extending recess with under-cut ends, and a face liner and side packing pieces contained in said recess and having ends fitting 15 snugly in the under-cut ends of the recess, the combined depth of the face liner and holder being less at the rear than at the front end thereof.

WALTER R. COZATT.
